SEWER FLUSHING DEVICE

Filed March 5, 1929

UNITED STATES PATENT OFFICE.

LOUIS F. KATONA, OF LOS ANGELES, CALIFORNIA.

SEWER-FLUSHING DEVICE.

Application filed March 5, 1929. Serial No. 344,218.

This invention relates to an improved type of sewer flushing device and is particularly directed to that general class of devices which automatically function to periodically discharge a predetermined volume of flush-
5 ing water into a sewer system.

A device of this general character comprises a flushing well having a valved outlet communicating with the sewer conduit to be flushed, said valve being arranged to be automatically opened by mechanism controlled by a predetermined head of water which is permitted to flow into the well at a predetermined preferably slow rate.

15 In a prior patent, No. 1,704,437, issued to me March 5, 1929, there is disclosed a device of this general nature having an improved type of valve which is operated by a tripping pan or bucket situated in a pit below the 20 floor-board of the well and adapted to receive the overflow from the well until said pan contains a sufficient weight of water to overbalance the weight of the valve so as to open said valve and release the water contained in the well, thus effecting the sewer 25 flushing operation.

In devices of this character, the positioning of the pan or bucket in a pit below the floor-board of the well, upon which floor-board the entire mechanism is supported and from which said pan is suspended, has proven to be objectionable in that it is extremely unaccessible for repair or adjustment and for the reason that in order to substitute a new pan for one which is no longer serviceable, it becomes necessary to dismount the entire upper structure and remove the floor-board.

It is therefore an object of the present 40 invention to provide a sewer flushing device of the general character referred to, in which all of the mechanism is positioned above the floor-board and is readily accessible for repair or replacement of parts.

45 In my prior patent above identified, there is disclosed a tubular type of flushing valve which extends above the maximum level of the water in the well so that the water will not by its weight tend to hold the 50 valve on its seat with such force as to require an excessive amount of power to effect an easy and quick opening thereof, and which is open throughout its length so that the discharge opening is in constant communication with the atmosphere above the

water in order to counteract suction influences tending to prematurely close the flushing valve during a sewer flushing operation.

Since this type of valve has proven to be of exceptional merit in actual service, it is 60 an object of the present invention to incorporate therewith an operating bucket and connecting mechanism, with said bucket disposed within such flushing valve in a position readily accessible for repair or re- 65 placement.

It is another and important object of the present invention to provide an improved form of connecting means between the flushing valve and the operating bucket, whereby 70 the descending element exerts an increasing elevating influence upon the ascending element throughout their strokes, this insuring more positive and quicker opening and closing movements of the flushing valve. 75

A further object is to provide a drain means for the operating bucket which will insure a proper draining of said bucket after each sewer flushing operation of the device.

Various other objects and advantages will 80 be more fully apparent from the following description of the accompanying drawings which form a part of this disclosure and which illustrate a preferred form of embodiment of the invention. 85

In the drawings:

Fig. 1 is a vertical section illustrating the flushing device of the present invention as mounted for operation within the well of a sewer system. 90

Fig. 2 is a partial plan section taken on the line 2-2 of Fig. 1.

Fig. 3 is an enlarged detail section taken on the line 3-3 of Fig. 1.

In the drawings, 10 designates a well of 95 any particular desired design, having at its top a manhole ring 11 closed by an inner pan 12 and an outer manhole cover 13, preferably located approximately level with the street or ground surface. 100

Below the floor level of the well 10 is a pit 14 located at the head of a sewer conduit 15, and mounted between the well 10 and the pit 14 is a floor-board 16, preferably formed of wood which has been treated with asphalt or other suitable material to render it water-tight, said floor-board being preferably calked in a metal frame 17 which is securely anchored in the masonry of the well. 105

This floor-board 16 forms a support for 110

the entire mechanism of the device and has a valved opening 18 therein constituting a discharge port establishing direct communication between the well and the sewer conduit 15. An annular tapered valve seat 19 is secured in said opening 18 by screws 20 and cooperating with said seat is a tubular valve 21 having a tapered valve ring 22 preferably formed of rubber and held in an annular groove in said valve by its inherent tension.

The upper sleeve portion 23 of the flushing valve 21 extends upwardly to a point somewhat above the maximum level of the water in the well and is of a substantially uniform diameter throughout its length so that the fluid head in the well will not exert an appreciable downward pressure thereon such as would tend to forcefully hold the flushing valve closed. This construction provides a tubular flushing valve which is open throughout its length and at all times communicates with the atmosphere so as to minimize suction influences tending to prematurely close the flushing valve and occasioned by the sudden discharge of the flushing water from the well.

This particular type of flushing valve is more fully described in my said prior patent, to which reference may be had for a more detailed explanation of its particular operation and advantages.

In the present device the flushing valve is guided in its vertical opening and closing movements by two opposed straps 24 which encircle the tubular extension 23 of the valve and are clamped by bolts 25 to diametrically opposite upright columns 26. These columns are preferably formed of pipe lengths having flanges 27 at their lower ends, by means of which they are secured to the floor-board 15, and they extend upwardly a considerable distance above the maximum water level, where they are connected together by a stationary cross-beam 28 removably secured to the uprights by set-screws 29 or by other suitable means.

The means employed for opening the flushing valve includes an operating bucket 30 which is located within the upper portion of the tubular valve extension 23, this bucket being suspended from connections carried by the stationary cross-beam 28 and in turn connected with the flushing valve in such a manner that as the bucket lowers, the flushing valve will be elevated, and conversely, as the valve closes, the bucket will be elevated to its normal position. The particular type of connecting means illustrated in the drawings comprises two vertically disposed bell-crank levers 31 and 34 pivoted respectively on opposite sides of the cross-head 28 and preferably parallel to each other and to the cross-head which is aligned with a diametric plane intersecting the axes of the flushing valve, the operating bucket, and the two up-

right columns, thus disposing the respective levers 31 and 34 on opposite sides of such diametric plane, as shown in Fig. 2.

The pivot 31^a of the lever 31 is offset, in the direction of said diametric plane, to one side of the axis of the bucket and flushing valve, and the pivot 34^a of the companion lever 34 is similarly offset to the opposite side of such axis, as is plainly shown in Figs. 1 and 2.

The lever 31 has an arm 32, the outer end of which is connected by a chain 32^c to an outwardly projecting ear 32^e secured to one side of the upper end of the flushing valve extension 23, and also has an oppositely extending arm 33, the outer end of which is connected by a chain 33^c to an outwardly projecting ear 33^e secured to one side of the upper end of the operating bucket 30. Similarly the lever 34 has an arm 35 having its outer end connected by a chain 35^c to an outwardly projecting ear 35^e which is secured to one side of the upper end of the flushing valve extension 23 diametrically opposite the ear 32^e, and also has an oppositely extending arm 36, the outer end of which is connected by a chain 36^c to an inwardly projecting ear 36^e secured to the upper end of the operating bucket 30 diametrically opposite the ear 33^e.

For convenience the arms 33 and 36 and the associated chains 33^c and 36^c may be termed inner arms and inner chains since they connect with the inner bucket 30, and the arms 32 and 35 and their associated chains 32^c and 35^c may be termed outer arms and outer chains since they connect with the outer flushing valve 23.

In the drawings the flushing valve is shown in its downward closed position and the operating bucket at this time is in its uppermost position. When the mechanism is thus normally disposed, the outer arms 32 and 36 of the respective bell-crank levers 31 and 34 assume more or less horizontal positions (as illustrated) and the inner arms 33 and 36 of said bell-crank levers assume angled positions preferably about forty-five degrees (45°); that is, the inner arm of each of the bell-crank levers 31 and 34 is angled approximately one hundred and thirty-five degrees (135°) in relation to its outer arm.

In the operation of the device, the operating bucket 30 receives sufficient water, through means to be later described, to overbalance the weight of the flushing valve, the weighted bucket thus becoming the source of power to open the flushing valve. During this valve opening operation the outer arms 32 and 35 of the bell-crank levers move from their horizontal positions to the angled positions indicated by dotted lines in Fig. 1, and the inner arms 33 and 36 move to horizontal positions. Thereafter the bucket 30 is emptied until the

weight of the flushing valve again overcomes the weight of the emptied bucket, whereupon the flushing valve will close and elevate the bucket through the chain and lever connections until the mechanism is again in the normal condition illustrated in the drawings.

Thus during the valve opening operation the bucket is the source of power, and the flushing valve, the weight to be lifted, and the inner arms 33 and 36, which are connected to the bucket, function as the power ends of the bell-crank levers, while the outer arms 32 and 35, which are connected to the flushing valve, function as the weight ends of said levers, and reversely, when the mechanism is returned to normal, the flushing valve becomes the source of power and the outer arms 32 and 35 function as the power ends of said bell-crank levers, while the bucket becomes the weight to be lifted and the inner arms 33 and 36 function as the weight ends of the bell-crank levers.

From an examination of bell-crank lever 31 as shown in Fig. 1 of the drawings, it will be evident that as the outer arm 32 moves upwardly to the angled position, indicated in dotted lines, the point of attachment of the associated chain 32^a gradually moves closer to a vertical plane intersecting the pivot 31^a of said lever, thus gradually decreasing the horizontal distance between said point and said pivot with a resulting gradual decrease in the effective lever-arm of the arm 32 which during this operation is the weight end of this bell-crank. In a reverse manner, and at the same time, the opposite arm 35 of said lever moves downwardly from its normal angled position to a horizontal position and its point of attachment with the associated chain 35^a gradually moves further away from said pivot intersecting plane thus gradually increasing the horizontal distance between said point and said pivot with a resulting gradual increase in the effective lever-arm of the arm 35 which during this operation is the power end of said bell-crank.

Now considering a reverse operation during which the flushing valve is closed and the mechanism restored to normal condition, it should be quite evident that the effective lever-arm of the arm 35 gradually decreases, however, since in this restoring operation it is the outer arm 32 which is the power end of the bell-crank instead of the inner arm 35, as in the valve opening operation, it follows that with this arrangement the effective lever-arm of whichever end of the lever is at the time functioning as power end will gradually be increased while the effective lever-arm of the opposite weight end will be gradually decreased. As both bell-crank levers are of duplicate proportions and are

similarly arranged, it will also be evident that they both function in like manner.

To limit the downward movement of the bucket 30 and the upward movement of the flushing valve, and to cushion these parts and the connecting mechanism against undue shock at the end of the valve opening operation, I provide a stop means for each bell-crank lever, preferably positioned in the path of the inner arm thereof. Each of these stop means comprises a bolt 38 which loosely passes through a metal washer 39 and a block 40 of rubber, and through a shelf 41 extending laterally from the cross-head 28, upon which shelf the block 40 rests. A nut 42 is screwed upon the lower end of said bolt below said shelf to limit upward movement thereof.

With this type of motion transmitting means the descending element exerts a gradually increasing elevating influence on the ascending element, thus insuring a more positive and a quicker opening and closing of the flushing valve than has heretofore been possible.

As shown in Fig. 1, the operating bucket 30 has an opening in its bottom wall and in this opening there is provided a tubular valve seat 43 secured in place by a lock-nut 44 engaging the screw-threaded shank 95 of said seat and clamping against the bottom wall of the bucket. A cap 45 is screwed upon the lower end of said valve seat shank and is provided with a discharge orifice 46 through which a guide rod 47 of 100 a drain valve 48 extends, said rod being considerably smaller in diameter than said discharge orifice to permit a free passage of fluid through said orifice. The valve 48 cooperates with the valve seat 43 and has an upwardly projecting operating rod 49 which extends through a bore in the cross-head 28, the upper end of said rod 49 having a laterally bent portion 50 slightly spaced from the upper surface of said cross-head when the mechanism is in normal condition with the drain valve 48 closed, this slight spacing of the bent over end 50 above the cross-head being for the purpose of allowing a free closing of said valve.

While it will be understood that various means may be employed to slowly fill the flushing well and to fill the operating bucket when the well becomes full, the means illustrated in the drawings, such means being of the type disclosed in my copending application Serial No. 341,598 filed February 21, 1929, will now be described.

The float controlled service valve mechanism includes a valve body 51 suitably secured to the cross-head 28 and having a pressure chamber 52 communicating with a service pipe 53 connected to the city water system or other source of water under pressure. A discharge chamber 54 communi-

cates with said pressure chamber 52, through a passage which is controlled by a service valve 55, and with a bucket filling conduit 56 of goose-neck form which extends upwardly a considerable distance and thence downwardly into the upper end of the bucket 30. The stem 57 of the service valve 55 extends downwardly through the valve body 51 and through a guide bracket 58 formed on said body and between the body 51 and the bracket 58 said valve stem 57 has a reduced portion 59 (see Fig. 3) providing opposed shoulders 60. Extending on opposite sides of said reduced portion 59 so as to engage the opposed shoulders 60 are two fork arms 61 of a valve operating lever 62, said arms being pivoted on a pivot pin 63 in the bracket 58 and the lever 62 being provided with a float 64 by means of which the valve 55 is operated. The wall of the pressure chamber 52 has a very small outlet port 65 through which the flushing water is discharged from the service line directly into the well, as indicated in Fig. 1, and the wall of the discharge chamber 54 has a drain port 66, said outlet port 65 being very minute as compared to the size of the service pipe 53 and the filling conduit 56; for instance, where these pipes are one-half inch in size, said port 65 will preferably be the size of a standard number sixty drill.

Describing the operation of the device, it is assumed that the mechanism is in a normal condition with the flushing valve seated and the service water turned on. Under these conditions the pressure of the service water acting upon the upper surface of the closed service valve 55 will tend to hold said valve closed and a very small portion of the service water will slowly discharge from the pressure chamber 52 through the minute port 65, thus slowly filling the main flushing well 10. In practice a sewer flushing well of ordinary size will have a capacity of about 300 gallons of flushing water and the filling jet discharged from the port 65 will be of such small volume that from twenty to twenty-four hours' time will be required in which to fill the flushing well.

As the water level reaches a proper predetermined height, as illustrated in Fig. 1, the water will exert a buoyant force upon the float 64 but until this force is sufficient to overcome the service water pressure exerted upon the upper surface of the closed service valve 55, the float 64 will remain in its normal lower position and become more submerged as the water level rises. When, through such increased submergence, the float has sufficient lifting power, the valve 55 will be opened. However, such opening will not be a slow gradual opening but will be a relatively quick opening since as soon as the valve 55 is "cracked" or just slightly

opened to allow a counterbalancing of pressures, upon opposite sides of the valve, the full elevating force due to the excess submergence of the float required to initially "crack" the valve, is no longer necessary; 70 therefore, the float thus relieved of the majority of its burden, will immediately bob upwardly to seek a higher level, more nearly floating upon the surface of the water, and effect a quick full opening of the service valve. This will be responsible for a corresponding lag in the time of closing of this valve, as will be later referred to.

Upon the opening of the service valve 55 when the well is filled to the desired level, 80 approximately the full service supply (excepting the small amount which continues to flow into the main well through the filling port 65, and a small amount which will, as later described, flow through a safety port 85 66) will flow through the goose-neck conduit 56 to fill the operating bucket 30.

The flow of service water into the operating bucket 30 will increase the weight hanging upon the inner arms 33 and 36 of the bell-crank lever arrangement which connects said bucket with the flushing valve 23 and when this weight overbalances the weight of the flushing valve, the operating bucket will start to descend to correspondingly open the flushing valve. Due to the increasing elevating effect produced by the descending operating bucket through the bell-crank lever connections, as previously explained, the opening of the flushing valve will be 100 quick and positive.

Further contributing to the positive opening of the flushing valve, will be the lag (previously referred to) in the closing of the service valve 55. Of course it will be understood that as soon as the flushing valve starts to open, the flushing water in the well will start to discharge into the pit 14 and sewer 15, through the opening 18, thus causing a lowering of the water level in the well. 110 However, due to the upward bob of the float 64 during the opening of the service valve 55, said valve 55 will not completely close until the water is at a much lower level than that which was required to cause the 115 said valve to "crack" and by reason of this lag in the closing of the service valve, the maximum flow of service water into the operating bucket 30 will continue for an appreciable time after the flushing valve starts 120 to open.

The operating bucket 30 retains all of the water which flows into it until said bucket descends a sufficient distance to cause the upper hooked end 50 of the stem 49 of the drain valve 48 to contact with the upper surface 125 of the cross-beam 28, whereupon said drain valve will no longer descend with the operating bucket but will remain suspended from the cross-beam 28, thus effecting an 130

opening of said drain valve. Upon opening of said drain valve the water contained in the operating bucket will start to drain through the drain port 46. However, the 5 size of this drain port is so proportioned in relation to the size of the well discharge opening 18 and the action of the mechanism, as to insure a complete emptying of the flushing well before sufficient water has 10 drained from the operating bucket 30 to cause a normalizing closing operation of the flushing valve and its associated mechanism.

In the operation of the practical device in actual service, the full opening movement of 15 the flushing valve is effected in a substantially instantaneous manner after the operating bucket is filled and an appreciable time will elapse before the water level in the well will lower sufficiently to effect a closing of the 20 service valve 55 and during this time the service water will continue to flow into the operating bucket at least as fast as it drains through the drain port 46. The flushing opening 18 is of sufficient size to discharge 25 the 300 gallons of water in the well in about thirty seconds and this discharge is so fast in relation to the draining of the weight water from the bucket through the drain port 46 that there is plenty of time for the 30 well to fully discharge its flushing water before the mechanism again starts to normalize.

As previously mentioned, the drain port 66 in the service valve body 52 is a safety 35 feature intended to take care of any ordinary leakage in the service valve; that is, in case of ordinary leakage the water leaking past the closed service valve 55 will drain through the port 66 in preference to flowing 40 upwardly over the goose-neck of the conduit 56, such port 66 being able to take care of valve leakage up to at least a leakage equal to the full draining capacity of such drain 45 port. This draining capacity is sufficient to take care of all ordinary valve leakage. However, if a leakage greater than said capacity occurs, the excess leakage will of course pass over into the operating bucket but this will only cause more frequent 50 operations of the device.

Such a situation will never occur in actual practice since this drain port 66 is approximately one-quarter of an inch in diameter and a valve leakage even approaching such 55 volume would be readily noted and eliminated by repair upon one of the regular periodic inspections to which all municipal sewer flushing devices are subjected.

It has been previously explained how the 60 "lag" in the full closing of the service valve causes the service water to flow into the operating bucket for an appreciable time after the flushing valve 21 starts to open. This is a desirable feature which is further augmented by the provision of the drain open-

ing 66 by reason of the fact that after the service valve 55 is opened and while the operating bucket 30 is being filled, said drain port 66 is discharging water into the well and thus continuing the raising of the water 70 level in the well and the greater submergence of the then stationary float 64 with such resulting delay in the closing of the service valve 55 in relation to the approximately instantaneous opening of the flushing valve 75 that the full service flow is continued until after the flushing valve is fully opened.

From the above description it will be apparent that I have provided an improved sewer flushing device in which the flushing 80 well is slowly filled by a minute flow from the service line and when the flushing water reaches a predetermined level, a float-controlled service valve is quickly opened to direct a major service flow directly into the 85 operating bucket until after said bucket and its contained water overbalance and operate the flushing valve by means of interconnecting bell-crank lever mechanism simultaneously effecting increase of the effective lever-arm of the power ends of said levers and a decrease of the effective lever-arm of the weight ends of said levers, and in which the operating bucket is provided with drain 90 means permitting emptying of said bucket 95 after the flushing well is emptied so as to cause a normalizing of the device.

The drain valve 48 is of particular advantage when the service pressure is so low that the water would drain from the bucket, 100 in the absence of the drain valve, as fast as water would flow into the bucket. However, in instances where the service pressure is relatively high so that water would in any event flow into the bucket faster than it 105 could possibly drain through the drain port 46, the drain valve 48 could, if desired, be dispensed with.

While it may be possible for the flushing valve to seat when its weight just slightly 110 overbalances the weight of the empty operating bucket, it is in practice desirable that the valve have an appreciable excess of weight so as to forcefully engage the valve seat to insure a water-tight closing of the 115 valve.

Since the valve closes under gravity influences, it will under such condition of excess valve weight close a great deal easier than it will be opened and therefore the weight 120 of water necessary in the operating bucket to open the valve will be proportionately in excess of that which would be required to open the valve if its weight just slightly overbalanced the weight of the empty 125 bucket. It is, however, evident that when the mechanism is operated with the flushing valve open and the drain valve 48 also open to permit the bucket to drain, the mechanism will normalize before all of the water has 130

drained from the bucket; that is, since the flushing valve will close just beyond a point of perfect counterbalance, such closing of the flushing valve will take place before the 5 excess weight water which was required to open the valve has had time to drain from the bucket, thus this excess water will become trapped in the bucket by reason of the closed drain valve 48 and will counterbalance the 10 excess weight of the flushing valve so that the aforesaid forceful seating of the flushing valve would not be present. Therefore, to insure a complete draining of the bucket under such condition, it is desirable to make 15 the valve 48 a buoyant valve which will operate in the following manner.

It will be evident that a buoyant valve will seat when the bucket is empty, as previously explained, and it will be understood 20 that it will remain seated while the bucket is being filled, due to the weight of water upon its upper surface. Now when the bucket drops to open the flushing valve, the drain valve 48 will be arrested by reason of 25 the hooked end 50 of its operating rod 49 engaging the cross-beam 28, as previously explained. When this occurs, the buoyant drain valve will float to the surface of the water in the bucket and will not again seat 30 until substantially all of the water has drained from the bucket, even though the bucket has in the meantime returned to its normal position to permit the flushing valve to seat.

35 It will thus be apparent that a buoyant drain valve will be of advantage in any instance in which there is a substantial predominant force tending to hold the flushing valve forcefully against its seat, and will 40 under all conditions insure a substantially complete draining of the operating bucket after each sewer flushing operation of the device.

45 While the particular embodiment herein illustrated and described is fully capable of fulfilling all of the objects primarily stated, it is to be understood that I do not desire to limit the present invention thereto for it is susceptible of embodiment in various other forms, all of which will come 50 within the scope of the following claims.

I claim as my invention:

1. In a sewer flushing device, the combination of: a well having an outlet communicating with a sewer; a valve closing said outlet; a stationary support; an operating bucket; and connecting means including a bell-crank lever pivoted on said support to oscillate in a vertical plane, said lever having an arm connected to said valve and adapted to move from a substantially horizontal normal position to an upwardly angled position with a gradual decrease of its effective lever-arm, and an opposed arm 60 connected to said bucket and adapted to

move from a normal upwardly angled position to a substantially horizontal position with a gradual increase of its lever-arm.

2. In a sewer flushing device, the combination of: a well having an outlet communicating with a sewer; a valve closing said outlet; a stationary support; an operating bucket; and connecting means between said valve and said bucket, said connecting means including two bell-crank levers pivoted to 70 said support for vertical oscillation, each lever having an outer arm connected to said valve and an opposed inner arm connected to said bucket, said outer arms each being adapted to move from a substantially horizontal normal position to an upwardly angled position with a gradual decrease of 75 its effective lever-arm and said inner arms each being adapted to move from an upwardly angled normal position to a substantially horizontal position with a gradual increase of its effective lever-arm.

3. In a sewer flushing device, the combination of: a well having an outlet communicating with a sewer; a valve closing said outlet and having a tubular extension open at its upper end; a stationary support; an operating bucket in said tubular valve extension; and connecting means between said valve and said bucket, said connecting means including two bell-crank levers pivoted to 90 said support for vertical oscillation, each lever having an outer arm and an opposed inner arm, the respective outer arms being connected to diametrically opposite sides of 95 said valve extension and adapted to move from substantially horizontal normal positions to upwardly angled positions with a gradual decrease of their effective lever-arms, and the respective inner arms being connected to diametrically opposite sides of 100 said bucket and adapted to move from upwardly angled normal positions to substantially horizontal positions with a gradual increase of their effective lever-arms.

4. In a sewer flushing device, the combination of: a well adapted to contain a body of flushing fluid and having an outlet communicating with a sewer; a valve closing said outlet and having a tubular extension extending above the maximum level of said body of fluid; an operating bucket suspended within said valve extension; a stationary support; and a balance connection between said valve and said bucket pivotally mounted 115 on said stationary support.

5. A device as defined in claim 4, in which said connection includes two relatively parallel bell-crank levers, each having a normally horizontal outer arm connected to said 125 valve extension and an opposed normally upwardly angled inner arm connected to said operating bucket.

6. A device as defined in claim 4, in which said connection includes two parallel bell- 130

crank levers disposed on opposite sides of a vertical plane diametrically intersecting the axis of said valve, with their respective pivotal centers disposed on opposite sides 5 of a vertical plane intersecting said axis at right angles to said first named plane, and in which each of said levers has a normally horizontal outer arm and an opposed normally upwardly angled arm, said outer arms 10 being connected by linkage to opposite sides of said valve extension, and said inner arms being connected by linkage to opposite sides of said operating bucket.

7. In a sewer flushing device, the combination of: a well adapted to contain a body 15 of flushing fluid and having an outlet communicating with a sewer; a flushing valve closing said outlet and having a tubular extension extending above the maximum 20 level of said body of fluid; an operating bucket suspended within said valve extension; a stationary support; a balance connection between said valve and said bucket pivotally mounted on said support, said 25 valve normally overbalancing the bucket to hold it elevated and the bucket being adapted to overbalance and open said valve when said bucket receives a predetermined amount of water; means for directing water 30 into said bucket when said body of flushing fluid reaches a predetermined level; and means permitting a relatively slow draining of the operating bucket after it operates the flushing valve.

35 8. In a sewer flushing device, the combination of: a well adapted to contain a body of flushing fluid and having an outlet communicating with a sewer; a flushing valve closing said outlet and having a tubular extension extending above the maximum level 40 of said body of fluid; an operating bucket suspended within said valve extension, said bucket having a restricted drain orifice; a stationary support; a balance connection 45 between said valve and said bucket pivotally mounted on said support, said valve normally overbalancing the bucket to hold it elevated and the bucket being adapted to overbalance and open said valve when said bucket receives a predetermined amount of 50 water; means for directing water into said bucket when said body of flushing fluid reaches a predetermined level; a drain valve closing said drain orifice when said bucket 55 is in elevated position; and means functioning to open said drain valve when the operating bucket descends, for permitting a relatively slow draining of the operating bucket after it operates a flushing valve.

60 9. In a sewer flushing device, the combination of: a well adapted to contain a body of flushing fluid and having an outlet communicating with a sewer; a flushing valve closing said outlet and having a tubular extension extending above the maximum level 65

of said body of fluid; an operating bucket suspended within said valve extension, said bucket having a restricted drain orifice; a stationary support; a balance connection between said valve and said bucket pivotally mounted on said support, said valve normally overbalancing the bucket to hold it elevated and the bucket being adapted to overbalance and open said valve when said bucket receives a predetermined amount of 70 water; means for directing water into said bucket when said body of flushing fluid reaches a predetermined level; a buoyant valve closing said drain orifice when said bucket is in elevated position and adapted to be held closed by the water flowing into said bucket; and means functioning to open said buoyant valve when the operating bucket descends, for permitting a relatively slow draining of the operating bucket after 75 it operates the flushing valve, said buoyant valve when opened by said means rising to the water level in said bucket so as to close only after substantially all of said water has drained from the bucket.

90 10. In a sewer flushing device, the combination of: a well having an outlet communicating with a sewer; a flushing valve closing said outlet; an operating bucket having a restricted drain orifice; a stationary support; a balance connection between said valve and said bucket pivotally mounted on said support, said valve normally overbalancing the bucket to hold it elevated and the bucket being adapted to overbalance and open said valve when said bucket receives a predetermined amount of water; means for directing water into said bucket when said body of flushing fluid reaches a predetermined level; a buoyant valve closing said drain orifice when said bucket is in elevated position and adapted to be held closed by the water flowing into said bucket; and means functioning to open said buoyant valve when the operating bucket descends for permitting a relatively slow draining of the operating bucket after it operates the flushing valve, said buoyant valve when opened by said means rising to the water level in said bucket so as to close only after substantially all of said water has drained from the bucket.

100 11. In a sewer flushing device, the combination of: a well adapted to contain a body of flushing fluid and having an outlet communicating with a sewer; a valve closing said outlet and having a tubular extension extending above the maximum level of said body of fluid; an operating bucket suspended within said valve extension; a stationary support; a balance connection between said valve and said bucket pivotally mounted on said stationary support; a service water pipe line for discharging service water directly into the operating bucket; a normally closed service valve in said pipe 105 120 125 130

line; means controlled by the body of flushing fluid in said well and functioning to open said service valve when the flushing fluid reaches a predetermined level and 5 thereby cause said bucket to be filled to overbalance and open the flushing valve and to close said service valve after the flushing

valve is opened; and means permitting a relatively slow draining of the operating bucket after it operates the flushing valve. 10

In testimony whereof, I have hereunto set my hand at Los Angeles, California, this 26th day of February, 1929.

LOUIS F. KATONA.
